UNITED STATES PATENT OFFICE

2,397,468

STEPLADDER

George W. Cail, Lafayette, Calif.

Application November 7, 1944, Serial No. 562,366

2 Claims. (Cl. 228—29)

This invention relates to stepladders.

It is the principal object of my present invention to provide a generally improved and simplified stepladder which can be expeditiously adjusted so that it can be properly supported on ground of irregular contour.

It is a further object of my invention to provide a ladder of the character referred to which can, by simple manipulation of the step section thereof, permit the supporting legs of the ladder to adjust themselves relative to the contour of the ground and be automatically latched in such adjusted condition.

In practicing my invention, I provide a ladder having the usual step section to the upper end of which is pivoted a latching leg which depends centrally and longitudinally of the step section and can be pivoted only in a plane toward and away from the step section. I also provide a supporting section which is connected at its upper end to the latch leg at a point short of the pivotal point of the latter. The connection referred to is such that the supporting section can pivot in a plane at right angles to the plane of movement of the latching leg. The connection also permits a limited amount of relative longitudinal movement between the latching leg and the supporting section. The latching leg and the support section are provided with complementary latching means which automatically disengage or engage upon relative vertical movement between the support section and the latching leg so that by simple manipulation of the step section, the supporting section may be released to adjust itself to the contour of the ground and then be automatically latched in this position relative to the latching leg by a release of the step section.

One form which the invention may assume is exemplified in the following description and illustrated by way of example in the accompanying drawing, in which:

Fig. 1 is a view in rear elevation of a stepladder embodying the preferred form of my invention.

Fig. 2 is a central vertical sectional view through the latching leg and supporting section taken on line 2—2 of Fig. 1.

Fig. 3 is a fragmentary view in vertical section showing the pivotal connection between the supporting leg and the step section taken on line 3—3 of Fig. 1.

Referring more particularly to the accompanying drawing, 10 indicates a stepladder embodying the preferred form of my invention. This

ladder is particularly adapted for use for orchard and other work where the supporting ground is of irregular contour. It has particular merit of automatic adjustment to the ground, where it is necessary to frequently change the position of the ladder to accommodate the user. Obviously, in orchards and on other uneven ground the supporting legs of the ladder must bear on a different plane than the legs of the step section. My ladder has such characteristics that it can accomplish this with a minimum of effort on the part of the user.

The ladder 10 comprises a step section 11 having the usual side legs 12 and steps 14. As in usual practice, the legs 12 of the step section 11 are divergent. At the upper end of the step section I have provided a pivot bolt 15 on which is pivoted a rigid plate 16, the pivotal connection being provided by inturned ears or lugs 17 formed as an integral part of the plate 16. The plate 16, of course, lies in a plane flatwise of the step section. Thus, the plate 16 may pivot in one direction only, which is toward and away from the face of the step section. Rigidly fastened at its upper end to the plate 16 is a latch leg 18 which is arranged at the rear face of the step section. This latch leg 18 depends longitudinally and centrally of the step section, as illustrated, and in that it is rigidly fastened to the plate 16, it can pivot only in a plane toward and away from the step section.

Arranged coextensively of the latch leg 18 is a support section 19 comprising two divergent legs 20 rigidly fastened together at their upper ends by plates 21 and intermediate their ends by rigid latch plates 22. The upper end of the support section 19 is positioned at a distance short of the pivotal point of the plate 16 and latch leg 18. The latch leg 18 extends between the two plates 21 and between the two latch plates 22 so that there can be no relative movement between the latch leg 18 and the support section 19 in the plane of the pivotal movement of the latch leg 18. The plates 21 are formed with aligned slots 23 engaged by a pintle 24 secured in the latch leg 18.

By this connection the support section 19 may pivot relative to the latch leg 18 in a plane at right angles to the plane of movement of the latch leg 18. Also, this connection permits a limited amount of relative vertical or longitudinal movement between the latch leg 18 and the support section 19.

To latch the support section 19 against pivotal movement with respect to the leg 18, the latch

plates 22 are formed with keeper notches 25. These notches are arranged at spaced distances apart transversely of the support section 19 and on an arc struck from the center of the slots 23. The keeper notches 25 are, of course, formed in the upper edge of the latch plates 22. To cooperate with these keeper notches 25 is a keeper 26 secured to the latch leg 18. When there is relative longitudinal movement between the support section 19 and the latch leg 18 causing the pintle 24 to be at the upper end of the slots 23, the keeper 26 will be withdrawn from the notch 25 which it has engaged and the support section 19 will be free to pivot about the pintle 24. Upon reverse longitudinal movement, disposing the pintle 24 in the lower ends of the slots 23, the keeper 26 will be engaged with an aligned notch 25. Thus, obviously, to adjust the ladder to the ground, it is merely necessary to give a sharp forward movement to the upper end of the step section which will upraise the latch leg 18 and disengage the keeper 26 from a notch 25. The support section 19 may then pivot to accommodate the lower ends of its legs 20 to the ground, and then opposite movement may be given to the upper end of the step section, re-engaging the keeper 26 with a notch which will then be aligned therewith, again latching the support section 19 from pivotal movement with respect to the latch leg 18 and the step section 11.

In operation of my ladder, it is constructed and assembled as illustrated and described. When it is set up in the orchard, a single movement by the user of the step-section automatically releases the support section 19 and enables proper adjustment thereof with respect to the ground and relatches the same with respect to the step section. It is not necessary that the user walk around the ladder to adjust the support properly to the ground, as the ladder can be adjusted by the user by simple manipulation of the step section.

Manifestly, I have provided by my invention an improved and simplified stepladder which can be efficiently used on ground of irregular contour, and which can be very expeditiously adjusted to suit the conditions met.

While I have shown the preferred form of my invention, it is to be understood that various changes may be made in its construction by those skilled in the art without departing from the spirit of the invention as defined in the appended claims.

Having thus described my invention, what I claim and desire to secure by Letters Patent is:

1. A ladder comprising a step section, an elongated latch leg pivoted at its upper end centrally of the upper end of the step section with its free end depending centrally and longitudinally of said step section a substantial distance for pivotal movement only toward and away from said step section, a support section arranged coextensively of said latch leg, a connection between the upper end of the support section and the latch leg at a point short of the pivotal end of the latter, said connection permitting pivotal movement of the support section relative to the latch leg in a plane at right angles to the plane of movement of the latch leg and relative longitudinal movement between the support section and the latch leg, cooperative latch means between the lower end of the latch member and the support section capable of latching the support section to the latch leg in various angular positions with respect to the latch leg, said latch means comprising a rigid latch plate fixed transversely of the support section and having keeper notches formed in its upper edge, and a keeper secured to the latch leg to engage said notches, engagement and disengagement of said keeper and notches being effected by relative longitudinal movement between the support section and the latch leg.
2. A ladder comprising a step section, an elongated latch leg pivoted at its upper end centrally of the upper end of the step section with its free end depending centrally and longitudinally of said step section for pivotal movement only toward and away from said step section, a support section comprising a pair of rigidly connected divergent legs, said support section being arranged coextensively of said latch leg, a connection between the upper end of the support section and the latch leg at a point short of the pivotal end of the latter, said connection permitting pivotal movement of the support section relative to the latch leg in a plane at right angles to the plane of movement of the latch leg, said connection permitting a limited amount of relative longitudinal movement between the latch leg and the support section, cooperative latch means between the lower end of the latch leg and the support section to latch the support section in various angular positions relative to the latch leg, said latch means being disposed a substantial distance below the upper end of the support section and being engaged and disengaged by relative vertical movement between the latch leg and the support section.

GEORGE W. CAIL.
